CLAIM

The ornamental design for an expandable sorter assembly, as shown and described.

DESCRIPTION

FIG. 1 is a front perspective view of one section of an expandable sorter assembly showing our new design, shown without the other two sections for convenience of illustration;

FIG. 2 is a front elevational view of one section of the expandable sorter assembly, shown without the other two sections for convenience of illustration;

FIG. 3 is a front elevational view of a second section of the expandable sorter assembly, shown without the other two sections for convenience of illustration;

FIG. 4 is a top view of one section of the expandable sorter assembly, shown without the other two sections for convenience of illustration;

FIG. 5 is a bottom view of one section of the expandable sorter assembly, shown without the other two sections for convenience of illustration;

FIG. 6 is a right side elevational view of one section of the expandable sorter assembly, shown without the other two sections for convenience of illustration;

FIG. 7 is a left side elevational view of one section of the expandable sorter assembly, shown without the other two sections for convenience of illustration;

FIG. 8 is an exploded front perspective view of the expandable sorter assembly showing all three sections; and,

FIG. 9 is an assembled front perspective view of the expandable sorter assembly showing all three sections.
